(57) **CLAIM**

The ornamental design for a light fixture, as shown and described.

DESCRIPTION

FIG. 1 is a bottom perspective view of a light fixture in accordance with my design, the shade portion having 180 degree rotational symmetry;

FIG. 2 is a top plan view of the light fixture in accordance with my design; and,

FIG. 3 is a bottom plan view of the light fixture in accordance with my design.

The broken lines showing environmental structure are for illustrative purposes only and form no part of the claimed design.
